Assistant Examiner — Bryan N. Melvin

(57) **CLAIM**

The ornamental design for an equipment for distribution of electric power and data signals as shown and described.

DESCRIPTION

1. Equipment for distribution of electric power and data signals

FIG. 1.1: Perspective front, top, left view of an equipment for distribution of electric power and data signals;

FIG. 1.2: Perspective back, rear, left view thereof;

FIG. 1.3: Right view thereof;

FIG. 1.4: Front view thereof;

FIG. 1.5: Back view thereof;

FIG. 1.6: Top view thereof;

FIG. 1.7: Rear view thereof; and

FIG. 1.8: Left view thereof.

The broken lines in the drawings represent bounds of the claimed design and are for illustrative purposes only. The broken lines form no part of the claimed design.

1 Claim, 8 Drawing Sheets
